UNITED STATES PATENT OFFICE.

THOMAS E. SMITH, OF GOOD SPRINGS, TENNESSEE.

CHURN.

Application filed January 3, 1923. Serial No. 610,452.

To all whom it may concern:

Be it known that I, THOMAS E. SMITH, a citizen of the United States, residing at #1, Good Springs, in the county of Giles and State of Tennessee, have invented certain new and useful Improvements in Churns, of which the following is a specification.

This invention relates to churns, and has for its object to set up a device of such class, 10 in a manner as hereinafter set forth, with a revolvable compartment container or churn body having arranged therein a fixed slotted dasher or abutment element forming the compartments of the container and providing 15 for the circulation of the body of milk through the compartments, when revolving the container during the churning operation, thereby greatly facilitating the latter with respect to the time employed in using an 20 ordinary form of churn apparatus, under such conditions providing for a saving in operating expenses.

A further object of the invention is to provide a device of such class with a container 25 or churn body having a removable cover and means for securing the cover to the container or churn body, in a manner to prevent any possibility of leakage of the contents of the container during the churning operation.

30 Further objects of the invention are to provide a churn which is simple in its construction and arrangement, strong, durable, compact, efficient in its use, conveniently operated, readily set up, permitting of access 35 to be had to the interior of the container, having means to prevent any possibility of leakage of milk during the churning operation, and comparatively inexpensive to manufacture.

40 With the foregoing and other objects in view, the invention consists of the novel construction, combination and arrangement of parts, as hereinafter more specifically described and illustrated in the accompanying 45 drawings, wherein is shown an embodiment of the invention, but it is to be understood that changes, variations and modifications can be resorted to which come within the scope of the claims hereunto appended.

50 In the drawings wherein like reference characters denote corresponding parts throughout the several views:—

Figure 1 is a perspective view of a churn in accordance with this invention.

55 Figure 2 is a vertical sectional view thereof,

Figure 3 is a section on line 3—3, Figure 2. A churn in accordance with this invention 60 comprises a revolvable counter-balanced container suspended on a supporting element consisting of a pair of side members 1, 2, a pair of end members 3, 4, secured upon the top edges of the side members 1, 2, at the ends thereof, through the medium of hold-fast devices 5, and the said supporting element further includes a pair of vertically disposed standards 6, 7, which are shoudered intermediate their ends as at 8, and mounted upon the top edges of the side members 1, 2, as well as positioned against the 65 inner face of each of side members. The standards 6, 7, are secured to the side members 1, 2, in any suitable manner, and each of said standards at its upper end is formed with a vertically disposed centrally arranged 70 slot 9, the bottom wall of which constitutes a bearing.

Arranged between the standards 6, 7, as well as suspended therefrom, in a manner as hereinafter referred to, is a container or 80 churn body consisting of a vertically disposed square body portion having rounded corners. The body portion is indicated at 10 and constructed of any suitable metallic material, has its upper end open, and its 85 lower end closed by a weighted bottom 11, the latter is formed with a depending grooved flange 12, into which the lower end of the body extends and is secured to thereby 90 providing a closed joint to prevent leakage 95 of the contents of the container.

Secured to the front, as well as to the rear of the body 10, is a connecting plate 13, having its intermediate and upper portion offset from the body 10, as indicated at 14, 15 95 respectively, and said upper portion of the plate 13, at each end thereof, is formed with a vertically extending apertured ear 16. Hold-fast devices, as shown rivets 17, are employed for fixedly securing the connecting 100 plates to the body 10. The intermediate portion 14 of each of the connecting plates 13, is positioned below the upper end of the body portion 10, and said upper end of the body portion 10 is bent upon itself as at 18, for 105 reinforcing purposes and also to provide for a snug fit in a cover element to be presently referred to.

Projecting from one side of the body 10 is a shaft 19, which is mounted in the slot of 110 the standard 6, and has one end provided with a pulley 20, for connection when de-

sired, with a driving means, not shown. Projecting from the other side of the body 10, is a shaft 21, provided with a crank arm 22, upon which is detachably mounted as at 23, a handle member 24, provided with a grip 25, for the purpose of manually operating the container 10. The shaft 21 is mounted in the slot 9, of the standard 7.

The container or churn body is formed 10 with a pair of compartments 26, 27, and the said compartments are provided through the medium of a stationary dasher or abutment element consisting of a rectangular body portion 28 disposed diagonally with 15 respect to the body portion 10, and extended from the bottom 11, to the cover element to be presently referred to. The body portion 28, of the dasher or abutment element is of the same width as the width of the 20 body portion 10, and when in position is interposed between the side walls of said body portion 10, as clearly shown in Figures 2 and 3. The upper edge of the body portion 28, is formed with a V-shaped cutaway portion or opening 29, having the walls thereof beveled as at 30, and the lower edge of the body portion 28 is also provided with a V-shaped cutaway portion or opening 31, having the walls thereof beveled as at 32, 25 but the walls of the opening 29 are beveled in an opposite direction with respect to the bevels of the walls of the opening 31. The top of the body portion 28 is flat, as at 33, so as to abut against the cover element to be 30 presently referred to, and the bottom of the body portion is flat as at 34, so as to abut against the bottom 11, of the body portion 10. The lower corners of the body portion 28 are rounded as at 35, so as to fit the 35 rounded corners of the body portion 10. One face of the body portion 28, for a portion of its length is inclined as at 36 with respect to the remaining portion of said face, and one portion of the other face of 40 the body portion 28, is inclined as at 37 with respect to the remaining portion of said face and by this arrangement the end portions of the dasher or abutment element are tapered. Each face of the dasher or 45 abutment element is formed with a transversely extending triangular shaped deflecting or agitating rib and the said ribs are indicated at 38, 39, and are oppositely disposed with respect to each other and are 50 further so arranged that they will project away from each other in opposite directions. The ribs 38, 39, are arranged substantially centrally with respect to the body portion 28 and are of the same width as the width 55 of the latter.

The openings 29, 30, permit of the circulation of the milk through the compartment 26, 27, during the revolving of the container or churn body.

60 The cover element is indicated at 40, and

is of a size as to project from the front and rear walls, as well as the side walls of the body portion 10, and the lower face of the cover element 40 is provided with longitudinal and horizontal grooves 41, 42, for the reception of the side walls and front and rear walls of the body portion 10, when the cover element is mounted in closing position, as shown in Figures 2 and 3. The reinforced ends 18, at the top of the body 75 portion 10, snugly fit the walls of the grooves 41, 42, when the cover element 40 is mounted in closed position.

The cover element 40 is clamped in closing position on the top of the body portion 80 10, by a pair of oppositely disposed clamping members, each of which consists of a curved body portion 43, extended through a pair of opposing ears 16 and having each end curved as at 44, to form a clamping 85 extension which bears on the upper face of the cover element and clamps the same against the top of the body portion 10, when the clamping members 43 are locked in position. The clamping members 43 are shiftably connected with the ears 16, and when moved to operative position, one member 43 extends over the other member 43, as clearly shown in Figure 1, and associated with the clamping members 43, is a shiftable T-shaped locking element 45, which when shifted to operative position overlaps and engages the clamping members 43 and locks them in operative position, so that the extensions 44 will bind against the element 40 100 and securely clamp it to the top of the body portion 10, in a manner to prevent leakage of the contents of the container or churn body during the revolving thereof.

The dasher or abutment element is disposed diagonally of the container or churn body, thereby providing the latter with a pair of compartments which communicate with each other through the openings 29 and 31 and when a body of milk is supplied 110 to the container, of a quantity to fill the container one-half or three-fourths, that portion of the container which is free of milk is filled with air and which practically accomplishes the churning during the revolving of the container. When starting the churning operation the major portion of the body of milk is under the dasher or abutment element and during the revolving of the container, the milk circulates from one 115 compartment to the other through the openings in the dasher or abutment element at the bottom thereof at every revolution of the container, and owing to the position of the dasher or abutment element in connection with the deflectors carried thereby, and the air within the container, the churning operation is greatly facilitated.

From the foregoing description taken in connection with the accompanying draw- 120

ings, a churn is set up which greatly facilitates the churning operation, and although the preferred embodiment of the construction is that as illustrated, yet it is to be

5 understood that changes in the detail of construction can be had without departing from the spirit of the invention as claimed.

What I claim is:

1. A churn comprising a revolvable container and a diagonally disposed imperforate rectangular dasher or abutment element arranged therein and providing said container with a plurality of compartments, said element formed with an opening having a cutaway portion at each end edge.

2. A churn comprising a revolvable container, and a diagonally disposed imperforate rectangular dasher or abutment element arranged therein and providing a plurality 20 of compartments in the container, said element having each end edge formed with a V-shaped cutaway portion.

3. A churn comprising a revolvable container, and a diagonally disposed imperforate rectangular dasher or abutment element arranged therein and providing a plurality of compartments in the container, said element having each end edge formed with a V-shaped cutaway portion, the walls of each 30 of said cutaway portions being beveled and with the bevel of the walls of one cutaway portion extending in opposite directions with respect to the bevel of the walls of the other cutaway portion.

35 4. A churn comprising a revolvable container, and a diagonally disposed imperforate rectangular dasher or abutment element arranged therein and providing a plurality of compartments in the container, said element having each end edge formed with a V-shaped cutaway portion, said element having each of its faces provided with a transversely extending rib.

45 5. A churn comprising a revolvable container, and a diagonally disposed imperforate rectangular dasher or abutment element arranged therein and providing a plurality of compartments in the container, said element having each end edge formed with a V-shaped cutaway portion, said element having each of its faces provided with a transversely extending rib, said ribs being oppositely disposed with respect to each other and triangular in contour.

55 6. A churn comprising a revolvable container, and a diagonally disposed imperforate rectangular dasher or abutment element arranged therein and providing a plurality 60 of compartments in the container, said element having each end edge formed with a V-shaped cutaway portion, the walls of each of said cutaway portions being beveled and with the bevel of the walls of one cutaway portion extending in opposite directions with respect to the bevel of the walls of the

other cutaway portion, said element having each of its faces provided with transversely extending rib.

7. A churn comprising a revolvable container, and a diagonally disposed imperforate 70 rectangular dasher or abutment element arranged therein and providing a plurality of compartments in the container, said element having each end edge formed with a V-shaped cutaway portion, the walls of each of said cutaway portions being beveled and with the bevel of the walls of one cutaway portion extending in opposite directions with respect to the bevel of the walls of the other cutaway portion, said element having each of its faces provided with a transversely extending rib, said ribs being oppositely disposed with respect to each other and triangular in contour.

8. A churn comprising a container, a cover element mounted thereon, means for detachably clamping said element to said container, and an imperforate dasher or abutment element arranged within and disposed diagonally with respect to said container 85 and extending from the bottom of the latter to said cover element, said dasher element having a V-shaped cutaway portion at each end.

9. A churn comprising a container, a cover element mounted thereon, means for detachably clamping said element to said container, and an imperforate dasher or abutment element arranged within and disposed 90 diagonally with respect to said container and extending from the bottom of the latter to said cover element, said dasher element having each of its faces provided with a transverse rib and each of its ends with a V-shaped cutaway portion.

10. A churn comprising a supporting element, a container revolvably mounted on said element and having an open top, a cover element detachably clamped to said container to close said top, and an imperforate rectangular diagonally disposed dasher element arranged within said container and providing the latter with a plurality of compartments, said dasher element extending 100 from the bottom of the container to said cover element and provided at each end edge with an opening.

11. A churn comprising a supporting element, a container revolvably mounted on said element and having an open top, a cover element detachably clamped to said container to close said top, and an imperforate rectangular diagonally disposed dasher element arranged within said container and providing the latter with a plurality of compartments, said dasher element extending from the bottom of the container to said cover element and provided at each end edge with an opening, and further provided with a transversely extending rib on each face.

12. A churn comprising a polygonal shaped revolvable container, and an imperforate rectangular diagonally disposed dasher element mounted therein and of the same width as the width of the interior of the container, said element extending from the bottom to the top of the container and providing the latter with a pair of compartments,

ments, said element having each of its end edges formed medially with a cutaway portion and said element provided on each of its faces, intermediate its ends, with a transversely extending rib.

In testimony whereof, I affix my signature hereto.

THOMAS E. SMITH.
